(57) **CLAIM**

I claim the ornamental design for the golf practice mat, as shown and described.

DESCRIPTION

A Golf Practice Mat to be used for the hitting surface and ball teeing area for the practice and playing of golf. A Golf Practice Mat to be used as a stance surface for the practice and playing of golf. A Golf Practice Mat with built in provisions for a one piece adjustable golf ball tee.

Application Number 29/188, 508 filing date Aug. 20, 2003, Name of Applicant James D. Slaven, Title of the Invention One Piece Adjustable Golf Ball Tee.

FIG. 1 is a plan view of the golf practice mat; and, FIG. 2 is a cross sectional view taken on line 2—2 of FIG. 1.
